US00D430663S

United States Patent [19]

Smart

[11] Patent Number: Des. 430,663
 [45] Date of Patent: ** Sep. 5, 2000

[54] MASK

[76] Inventor: **Gregory Scott Smart**, 30 Howard St., Randwick, New South Wales, 2031, Australia

[**] Term: 14 Years

[21] Appl. No.: 29/101,861

[22] Filed: Mar. 12, 1999

[30] Foreign Application Priority Data

Dec. 9, 1998 [AU] Australia 3924/98

[51] LOC (7) Cl. 29-02

[52] U.S. Cl. D24/110.4

[58] Field of Search D24/110.1, 110.4, D24/110.5; 128/207.13, 207.12, 207.11, 207.17, 206.24, 205.25, 206.21, 206.2, 207.18, 206.11, 206.26, 206.12
